2,192,463

INNER-SPRING UNIT FOR MATTRESSES

Arthur Wesley, Chicago, Ill., assignor to Burton-Dixie Corporation, Chicago, Ill., a corporation of Delaware

Application October 21, 1938, Serial No. 236,197

3 Claims. (Cl. 5—248)

One of the leading objects and prime purposes of the current invention is to provide an improved and novel type and style of spring-assembly adapted for use in inner-spring mattresses and for employment in similar or comparable relations.

An outstanding and paramount aim of the invention is to supply a spiral-spring unit of the kind referred to in which the supporting capacities of the various springs of the structure are varied or graduated to conform substantially to the loads to which they are subjected in service.

The central portion of a person's body is heavier than the head and legs, and, accordingly, that middle part of the spring structure is made of greater carrying capacity without, however, decreasing the comfort of that section of the spring and mattress to the occupant.

Again, the border or margin of such a mattress is frequently subjected to greater usage and loads than other parts, as by a person sitting on the edge portion of a mattress, and, therefore, such border sections should be of greater capacity or stiffer than other parts of the spring-unit within the mattress.

Conforming these springs to their several loads and at the same time preserving their comfort and ease to the occupants throughout the whole area of the mattress is not such a simple matter as it may at first appear to be.

For example, in a spring-unit having 19 cross rows of upright spiral-springs and 11 lengthwise rows of such springs, the single row of springs around all four edges of the assembly may be considered as the border-springs, the 9 rows of cross-springs (9 in each row) at the middle portion of the spring-unit may be designated as the central-springs, and the remaining two sets of 4 cross-rows of springs (9 in each row within the border-springs) may be denominated as the end-springs.

All of the border-springs are made alike, all of the end-springs have the same structure, and all of the central-springs are the same in construction.

The end-springs have the least supporting capacity and each may be considered as of unit strength.

On the other hand, each border-spring while of the same form as each end-spring, is made of one-half gauge heavier wire to provide a stiffer margin for the spring-unit.

The center section of the assembly must carry a greater weight than the end sections by reason of the fact that, as stated above, the middle por-

tion of a person's body is of materially greater weight than the head and legs which are supported by the two end sections of the unit, and, accordingly, the springs constituting such central section are each made of greater carrying capacity.

This is accomplished, in the present preferred embodiment of the invention, by using wire of one-half gauge greater size than that of which the end-springs are made, but this would make the center of the unit objectionably stiffer than the remainder, and, to overcome such inconvenient or discommodious feature, each such central-section spring is given one more complete convolution than the end-springs, this being done to afford each such spring a greater volume of wire to support the greater load and to make each such spring of greater height, say one-half inch, over the end springs, thus providing the assembly with a slight crown throughout its central zone.

That is to say, each of these central-zone or middle-area springs, in order to perform its extra duty, is increased in height, made of a greater number of convolutions, and is formed of wire of augmented gauge.

This is not all, however, since, in order to offset, or to compensate, for the naturally softer and more resilient effect resulting from the use of the added turn or convolution of the wire in each spring, the diameter of the center convolution of the spring is reduced, in some instances, about $\frac{1}{8}$ inch, as otherwise the extra turn of the wire would make the central-springs softer than the end-springs.

Should these central-springs be merely stiffer than the others, as would happen if the same windings in number and pitch and diameter as the end-springs were used, with merely an increase in the weight of the wire, they would be uncomfortably objectionable.

However, by making the several cooperative changes specified, all undesired factors are compensated for and the central-springs are not appreciably stiffer than the end-springs although they have more carrying or supporting power.

So far as is known, these features are new and the results accruing therefrom provide a spring-unit with unusual characteristics of comfort for, and enjoyment by, the occupants of the mattress incorporating such resilient or elastic structure conforming in its various parts to the different weights of the several portions of the body of a normal human being.

trating the present preferred embodiment of the invention described above and in the several views of which drawings like reference numerals have been used to designate the same parts:

- 5   Figure 1 is a plan view of the spring-unit;
Figure 2 is a fragmentary vertical section on an enlarged scale on line 2—2 of Figure 1; and
Figure 3 is a partial vertical section on a similar enlarged scale on line 3—3 of Figure 1.
- 10   Referring to these drawings, the border-springs 11 may be of wire of 13½ gauge and 5 inches high, the center-springs 12 may be of wire of 14 gauge 5½ inches high, and the end-springs 13 may be of wire of 14½ gauge and 5 inches high, these several springs being joined together in any approved manner to form a complete unit or assembly, as by the employment of helical-springs 14 interlocked with the end rings or convolutions of the springs.
- 15   In the drawings, the differences between the springs have been purposely exaggerated somewhat to make such differences more apparent or conspicuous.
- 20   Those acquainted with this art will, of course, understand that the invention as defined by the appended claims, which should be construed or interpreted as generically as the state of the prior art will permit, is not necessarily limited or restricted to the precise and exact details presented and that modifications and changes may be resorted to without departure from the underlying

principles of the invention and without the loss or sacrifice of any of its material benefits and advantages.

I claim:

1. In a mattress inner-spring unit, the combination of upright spiral-springs arranged in longitudinal and transverse rows and means fastening said springs together to form a spring-unit, the longitudinal border-springs being of larger gauge wire than the springs forming the two transverse end-sections of the unit exclusive of their border-springs, the springs constituting the transverse central-section of the unit, exclusive of its border-springs, each being of heavier gauge wire, of greater height, and of more turns than the springs of said end-sections, said longitudinal border-springs being of practically the same height, said central-section springs being of practically the same height, and said end-section springs being of practically the same height.

2. The mattress inner-spring unit set forth in claim 1 in which said transverse central-section springs have their center convolutions of less diameter than that of said end-section springs.

3. The mattress inner-spring unit set forth in claim 1 in which both the longitudinal and transverse border-springs are of larger gauge wire than the springs forming the two transverse end-sections of the unit.

ARTHUR WESLEY. 30
